(57) **CLAIM**

The ornamental design for a diagnostic device, as shown and described.

DESCRIPTION

FIG. 1 is a perspective view of one embodiment of the diagnostic device that illustrates the novel design; FIG. 2 is a top view of the diagnostic device of FIG. 1; FIG. 3 is a right view of the diagnostic device of FIG. 1; FIG. 4 is a left view of the diagnostic device of FIG. 1; FIG. 5 is a front view of the diagnostic device of FIG. 1; FIG. 6 is a rear view of the diagnostic device of FIG. 1; FIG. 7 is a bottom view of the diagnostic device of FIG. 1; FIG. 8 is a perspective view of the diagnostic device that illustrates a second embodiment of the novel design; FIG. 9 is a top view of the diagnostic device of FIG. 8; FIG. 10 is a right view of the diagnostic device of FIG. 8; FIG. 11 is a left view of the diagnostic device of FIG. 8; FIG. 12 is a front view of the diagnostic device of FIG. 8; FIG. 13 is a rear view of the diagnostic device of FIG. 8; and, FIG. 14 is a bottom view of the diagnostic device of FIG. 8. The dashed lines in the drawings are for illustrative purposes only and form no part of the claimed design.
